UNITED STATES PATENT OFFICE.

FRANK S. IRVINE, OF HUNTINGTON, NEW YORK, ASSIGNOR TO WESTERN ELECTRIC COMPANY, INCORPORATED, OF NEW YORK, N. Y., A CORPORATION OF NEW YORK.

AUTOMATIC SWITCH.

Application filed September 22, 1920. Serial No. 411,880.

To all whom it may concern:

Be it known that I, FRANK S. IRVINE, a citizen of the United States, residing at Huntington, in the county of Suffolk, State 5 of New York, have invented certain new and useful Improvements in Automatic Switches, of which the following is a full, clear, concise, and exact description.

This invention relates to automatic switch- 10 ing devices and more particularly to switches of the type used in telephone systems for extending talking connections.

Where non-numerical or finder switches are employed for seizing and extending sub- 15 scribes' lines either to succeeding selective switches or to operators' positions, a convenient method of handling incoming calls is to divide the subscribers' lines into groups and to assign the requisite number of finder 20 switches to serve each of such groups of lines. If the capacity of the finders is large it is desirable to provide the finders with a plurality of sets of brushes, each brush set having access to a group of lines. By this 25 arrangement only the particular brush set having access to the group of lines containing the calling line need be taken for use. Accordingly the finder is not required to move over the entire group of lines it serves, 30 but only over a smaller group individual to a set of brushes in hunting and seizing a calling line.

It is imperative that the period consumed by the finder switch in seizing a calling line 35 be made as short as possible, especially where the lines are extended to switches or register mechanisms that are to be controlled by impulses sent from the substation. To materially reduce the hunting time it is proposed to 40 divide each brush group into two subgroups and to connect the lines to the terminal banks such that one subgroup of lines appear as first choice lines to the brushes of half of the finders and as second choice lines to the 45 brushes of the remaining finders. Likewise the second subgroup of lines appear as first choice lines to the second half of the finders and as second choice lines to the first half of the finders. Normally, when a call originates 50 in one of the subgroups a finder having first choice access to this subgroup is taken for use. Hence, the finder is only required to move over the first half of a brush group. When all finders, having access 55 to a subgroup as first choice, are en-

gaged and a call originates in that subgroup, one of the finders having second choice access to the subgroup is utilized, if any of these be idle at the time.

As above stated a plurality of finders are 60 provided for serving each of the subgroups. The first group of finders, for example, normally serve as first choice the first subgroup of lines of all brush groups appearing in those particular finders. The second group 65 of finders normally serve as first choice the remaining subgroup of all brush groups. Since both groups of finders consist of a plurality of equivalent switches means is necessarily provided to select an idle one for 70 use in handling an incoming call. This is accomplished by the use of a series starter wire. To equalize the distribution of wear on the several finders of each group it is proposed to arrange the circuits such that 75 the preferred order in which the finders of a group are taken for operation is shifted at each call.

Accordingly, the object of the present invention is to provide means, in a system of 80 the foregoing character, whereby the order of preference, in which the finders of either group are taken for use, is changed regardless of whether said finders are operated to serve one of their first choice lines or one 85 of their second choice lines.

A feature of the invention relates to means operative each time a finder in either group is operated to extend a line to change the order in which the finders, of the group containing the operated finder, may be taken for use. 90

Other and further features contemplated by the invention will become more apparent 95 from the following description.

Referring particularly to the drawing, Figs. 1 to 7 inclusive, when arranged in the order illustrated in Fig. 8, disclose a portion of a telephone exchange system in which the principles of the invention are incorporated. 100

Fig. 1 shows two subscribers' lines, one in each subgroup of a group of lines, served by the same set of brushes of the finder switch. This figure also shows the individual line relays and the group relays which control a series circuit for initiating the operation of the finder switches. 105

Fig. 2 illustrates diagrammatically a subscriber's line in each of the two subgroups 110

of two other brush group of lines. Here the line and group relays are shown and also the manner in which the group relays of the several brush groups cooperate to control the series circuit that determines the initiation of the movement of a finder switch in response to a call.

Figs. 3 and 4, taken together, show a group starter circuit common to all the brush groups of subscribers' lines, of which three are indicated in Figs. 1 and 2, for starting in operation the proper one of a plurality of line finder switches in response to the initiation of a call. At the left of Fig. 3 is illustrated one element of a preference switch for determining the order in which the several corresponding subgroups of lines may gain access to the starter circuit. To the right of this figure is illustrated a switch for determining the preferred order in which the finders of a first group are taken for use. At the left of Fig. 4 is shown the second element of the preference switch for determining the order in which the second subgroups of all brush groups may obtain access to the common starter circuit. At the right of Fig. 4 is shown another switch similar to the one illustrated at the right of Fig. 3 and serving to change the order in which the several finders of a second group are taken for use.

Fig. 5 shows in detail portions of the structure and circuits of one of the finder switches of the first group. Within the small broken rectangles in the lower right-hand part of the figure are shown certain elements of three finder switches belonging to the same group.

Fig. 6 illustrates in diagrammatic form certain parts of the structure and circuits of four different finder switches of the second group.

Fig. 7 illustrates a district or first selector switch to which calling lines are extended by the finder switch shown in detail in Fig. 5.

The line finder switches used in this system are of the well-known power driven panel type. The corresponding brushes of a plurality of finder switches serving the same group of subscribers' lines are arranged to be tripped into active relation with the terminal bank by means of a common trip rod, such as shown and described in the patent to McQuarrie, 1,177,044, issued March 28, 1916.

The district selector switch illustrated diagrammatically in Fig. 7 may also be of the power driven panel type and is similar in construction to the switch disclosed in the patent to Craft and Reynolds, 1,123,696, issued January 5, 1915.

The preference switch shown at the left of Figs. 3 and 4 is an ordinary rotary step-by-step switch, the brushes 304 and 404 of which cooperate with corresponding arcuate

terminal banks having as many terminals as may be desired. These brushes are driven in their step-by-step movement by the stepping magnet 408, shown in Fig. 4. The two preference switches, shown on the right-hand side of Figs. 3 and 4, are likewise step-by-step devices each comprising a pair of brushes and corresponding terminal arcs. The brushes of these switches are driven by the stepping magnets 307 and 407 respectively.

In order that a better understanding may be had of the purpose of the invention, a general description will first be given of the grouping arrangement of the subscribers' lines in a system of this character. It may be assumed for the purpose of illustration that the subscribers' lines, such as 100, 110, 200, 210, etc. are divided in major groups of 300 lines each. Accordingly, the finder switches, in the terminal banks of which the subscribers' lines appear, each have a capacity of 300 lines. It may further be considered that the finder switches are provided with 15 sets of brushes, each set of brushes, consequently, having access to 20 subscribers' lines. With the arrangement of tripping brushes used in switches of this character, it is only necessary for the finder to move a distance corresponding to a brush group of 20 lines to seize and make connection with any calling line. That is, when a subscriber initiates a call the particular set of brushes of an idle finder switch having access to the group containing his line is tripped and moved over the terminals of the group in search of such line. By thus dividing the total group of lines into smaller brush groups the time required for finding a calling line is materially reduced.

In order to further decrease the hunting time of the finder switch the brush groups of lines are subdivided into two groups of ten lines each, which for convenience will be designated hereinafter as the A and B groups. Referring to Figs. 1 and 2, it will be noted that the lines 100, 200 and 220 each belong to the A group of their respective brush groups, while lines 110, 210, 230 belong to the B groups of the same brush groups. In other words there are ten lines similar to 100 in the A subgroup, and ten lines similar to 110 in the B subgroup of the particular brush group of twenty lines illustrated in Fig. 1. Similarly the same applies to the lines shown in Fig. 2 for all of the remaining brush groups which are not shown in the drawing. Conforming with the subdivision of a brush group of lines into the A and B sub-groups, the entire group of line finder switches serving a major group of 300 lines is divided into two groups designated the A and B groups, and each contains an equal number of switches. Obviously, the total number of finders assigned to serve a major

group of 300 lines may be taken to suit the requirements and is governed largely by the volume of the traffic. Whatever this number may be it is divided equally or otherwise, if desired, into two groups, one of which, the A group, normally serves subscribers' lines in the several A subgroups, and the other, the B group of finders, normally serves the subscribers' lines in the B subgroups. The finders of the A group are illustrated in Fig. 5, and those of the B group in Fig. 6.

Referring to Fig. 5, one brush set and the section of the terminal bank cooperating therewith is illustrated. This section of the terminal bank is shown divided into two sections, a lower section and an upper section. The subscriber's line 100, which belongs to the A subgroup, terminates in terminals 516, 517, 518 and 519 of the lower section of terminals in the finder switch. The subscriber's line 110, located in the B subgroup, terminates in the terminals 526, 527, 528 and 529 of the upper section in the finder switch. In a similar manner the ten subscribers' lines of the A subgroup appear in the lower sections of terminals served by the corresponding brushes of the remaining finders of the A group. The ten subscribers' lines of the B subgroup appear in the upper sections of terminals of the corresponding brush sets of all finders in the A group.

Turning to Fig. 6 it will be seen that the subscriber's line 100, which appears in the lower section of terminals in the A finder switches, terminates in terminals 615, 616, 617 and 618 of the upper section of terminals served by the brush set 604 of finder 600 of the B group of finders. In a similar way line 100 and the remaining lines of the A subgroup are multiplied to corresponding terminals in the upper section served by the corresponding brush sets of the remaining finder switches 601, 602, 603, etc. of the B group. Conversely, the lines, such as 110 of the B group, which appear in the upper groups of terminals in the A finders, are seen to be multiplied to terminals 620, 621, 622 and 623 of finder 600, terminals 624, 625, 626 and 627 of finder 601, and to corresponding terminals in the lower sections served by the brushes of the remaining finders 602, 603, etc. of the B group. The ten lines, such as 200 of the subgroup of the second brush group, would appear in a similar manner in the lower half of the sections served by a second set of brushes of each of the A finders, and in the upper half of the sections served by corresponding brushes of the B finder switches. Similarly, lines, such as 210 of the B subgroup of this particular brush group, would appear in the upper half of the brush section at the A finders, and in the lower half at the B finders. The same may be said of the lines of all remaining brush groups.

Briefly stated, by this grouping arrange-

ment the lines of the A subgroup of each of the fifteen brush groups of lines appear as first choice lines in the A finder switches, and as second choice lines in the B finder switches. The lines of the B subgroups of 70 each of the fifteen brush groups, in a like manner, appear as first choice lines in the B finder switches and as second choice lines in the A finder switches. Consequently, whenever a call is initiated in one of the A 75 subgroups, an A finder switch, if one be idle, is set in operation to find the calling line and in so doing need traverse only a maximum of ten terminals. When a line in one of the B subgroups initiates a call, one of the B 80 finder switches, which has first choice access to such line, is started in operation. Should a line originate a call in the A group when all of the A finders are busy, then, by means hereinafter to be explained, one of the B 85 finder switches is taken for use and must first traverse the lower section of ten terminals before it can enter the upper section to search for the calling line. In a similar fashion should a line in the B group 90 initiate a call when all B finders are busy, then an A finder is taken for use, if one be idle at this time, to extend the calling line.

Where the series starter wire is employed for controlling the starting of an idle finder switch of a plurality of switches, experience shows that an unequal distribution of wear on the switches is certain to result. If all finders be idle and a call comes in, the first finder in the series is taken for use. If during the busy period of the first finder another call occurs, the second finder in order is used. Only when a large number of simultaneous calls occur will the switches toward the latter end of the series be 105 utilized. Hence, it is obvious that the switches in the first of the series will bear the greater part of the work. To overcome this undesirable condition a preference switch is provided, the function of which is 110 to shift, from time to time, the order in which the finders of a group are taken for use. The switch indicated at the right of Fig. 3 performs this function with respect to the finders of the A group shown in Fig. 115 5. The preference switch shown to the right in Fig. 4 cooperates similarly with the several finders of the B group. Whenever a finder switch in either group is taken for use the preference switch, serving such 120 group is advanced one step whereby a new order of preference in the appropriation of an idle switch is established. In this way the number of times that any particular switch is operated is substantially equal to 125 the number of operations made by each of the other switches of the group.

It is desirable that the order in which the finders of either the A or B groups are taken for use may be shifted after the operation 130

of any finder in such groups, regardless of whether such finder serves a line in the A subgroup or a line in the B subgroup. Accordingly, it is the purpose of this invention 5 to provide a circuit arrangement whereby the preference switch governing the order in which a group of finders are taken for use may be advanced whenever one of such finders is operated either to serve a line to which 10 it is normally allotted or to serve one of its second choice lines as in the case when all the finders in the other group are engaged. Having given a general explanation of the 15 system, it is now thought that a detailed description of the operations involved in the extension of a calling line will be helpful in obtaining an understanding of the invention.

It will be assumed that the subscriber to 20 line 100 wishes to obtain a telephone connection. Upon removing his receiver from the switch hook a circuit is established from battery through the winding of line relay 104, inner left-hand armature and contact 25 of cut-off relay 103, line conductor 102, through the loop of the calling substation, line conductor 101, contact and right-hand armature of relay 103 to ground. Relay 104 becomes energized and completes a circuit 30 from ground through its contact and left-hand armature, conductor 115, group relay 105, common to the ten lines of the A group to battery and ground. Relay 105 becomes 35 energized and completes a circuit from ground through its contact and armature, contact and armature of relay 106, left-hand armature and back contact of relay 107, left-hand winding of relay 108, conductor 116, outer left-hand armature and contact of relay 302, outer left-hand armature and contact of relay 402, contact and armature of stepping magnet 408 to battery and ground. Relay 108 attracts its armatures 40 and closes a holding circuit for itself as follows; ground, right-hand contact of relay 107 right-hand winding and contact and inner right-hand armature of relay 108, conductor 117, terminal 309, brush 304, left-hand armature and back contact of relay 50 300, conductor 310, back contact and right-hand armature of relay 401, conductor 311, winding of relay 302 to battery and ground.

The brushes 304 and 404 of the preference switch are assumed to be standing on their 55 first position terminals in which position first preference is given to lines in the A and B subgroups of the first brush group shown in Fig. 1. In the event that a call should originate in this brush group simultaneously with the initiation of a call in any of the other brush groups, such as those shown in Fig. 2, first preference is given to that particular brush group whose relay, such as relay 108 or 118, may obtain a locking 60 circuit through its right-hand winding

directly through the wiper 304 or 404 without first passing through the back contacts and armatures of relays corresponding to relays 108 and 118 in other brush groups. With the preference switch in the position indicated in the drawing, the holding circuit for the right-hand winding of relay 108 is seen to lead directly through the terminal 309 and brush 304, thus giving first choice to lines in the A group of the first 75 brush group.

The relay 302 becomes energized in series with the right-hand winding of relay 108, and this latter relay remains energized. Relay 108, at the same time, completes a circuit for the trip magnet 505, which governs the tripping of the particular set of brushes in all finders of both A and B groups, which

have access to the terminals of the calling line 100. This circuit leads from ground through the inner left-hand armature and contact of relay 108, conductor 124, winding of trip magnet 505 to battery and ground. Relay 302, at its outer left-hand armature and contact, opens the circuit to the conductor 116, thereby preventing the energization of the relay similar to relay 108 in any other brush group. Relay 302, at its inner right-hand armature and contact, closes a circuit from ground over conductor 312, through the winding of stepping magnet 408, to battery and ground. Magnet 408 becomes energized preparatory to advancing the brushes 304 and 404 to their next position terminals. Relay 302 also completes a circuit from ground through its outer right-hand armature and contact, conductor 313, left-hand make-before-break contact of relay 303, brush 306, terminal 314, conductor 315, inner left-hand armature and back contact of relay 500, winding of relay 504 to battery and ground. Relay 504 becomes energized and locks up in a circuit from battery through its winding and contact and inner left-hand armature, conductor 530, contact and armature of relay 522 to ground. Relay 504 completes a circuit from ground through its outer left-hand armature and front contact, contact and outer right-hand armature of relay 500, conductor 316, right-hand make-before-break contact of relay 303, winding of said relay to battery and ground. Relay 303 becomes energized and locks up in a circuit from battery through its winding and right-hand armature and make-before-break contact, conductor 313 to ground at the outer right-hand armature of relay 302. Relay 303 completes a circuit from battery through the winding of stepping magnet 307, brush 305, left-hand armature and contact of relay 303, conductor 313, contact and outer right-hand armature of relay 302 to ground. The magnet 307 becomes energized and prepares to 90

advance the brushes 305 and 306 forward 100

110

115

120

125

130

one step when the circuit of said magnet is opened.

Relay 504 also closes a circuit at its right-hand armature and contact for the up-drive power magnet 506 of the finder switch shown in detail in the drawing. As will more fully be explained later, the selection of this finder switch for use is based on the assumption that the brush 306 of the preference switch is standing in the position shown and that said finder is idle at the time the call originates. The power magnet 506 causes the upward movement of the brush shaft 508. Since the trip magnet 505 is energized in the circuit above described, the trip spindle 511, which is common to the brush sets of all finders in the A and B groups shown in Figs. 5 and 6, is rotated to its set position. The first upward movement, therefore, of brush 508 causes the brushes 512, 513, 514 and 515 to be tripped so as to engage the terminals of the bank. Shortly following the tripping of the set of brushes, the brush 520 encounters the metallic segment 531 and a circuit is closed from ground through brush 520, segment 531, outer left-hand armature and contact of relay 523, conductor 317, back contact and inner left-hand armature of relay 301, conductor 121, contact and outer left-hand armature of relay 108, winding of relay 107 to battery and ground. Relay 107 becomes energized and locks up in a circuit from battery through its winding and front contact and left-hand armature, conductor 122, armature and contact of relay 106 to ground at the armature and contact of relay 105. Relay 107, at its right-hand contact, opens the holding circuit of relay 108, whereby this latter releases its armatures. The deenergization of relay 108 causes the opening of the circuit of trip magnet 505 and the common brush trip rod 511 restores to its normal position. Relay 108, furthermore, opens the circuit of relay 302, which becomes deenergized. Relay 302, at its outer left-hand armature and contact, closes the conductor 116 so that further calls in the same or other brush groups may now gain access to the common starter circuit. Relay 302, at its inner right-hand armature, opens the circuit of magnet 408, which becomes deenergized and advances the brushes 304 and 404 of the preference switch to their next position terminals. Relay 302, at its outer right-hand armature, opens the circuits of relay 303 and magnet 307. Relay 303 releases its armatures while magnet 307 becomes deenergized to advance the brushes 305 and 306 forward one step. At the time relay 107 becomes energized as the finder switch passes out of the brush tripping zone, a circuit is closed for the right-hand winding of relay 106. This winding, however, is non-inductively wound and does

not produce sufficient magnetic flux to cause the attraction of the armature of relay 106.

The brush shaft 508 of the finder switch continues its upward movement in search of the terminals of the calling subscriber's line. 70 When brushes 512, 513, 514 and 515 encounter terminals 516, 517, 518 and 519, a circuit is closed from ground through the outer right-hand armature and contact of relay 523, winding of test relay 522, brush 512, terminal 516, conductor 123, right-hand armature and front contact of relay 104, contact and outer left-hand armature of relay 103, left-hand winding of relay 106 to battery and ground. The test relay 522 becomes energized in this circuit and opens the holding circuit of relay 504. Relay 504, however, is maintained energized in a circuit over conductor 530, commutator 521 and brush 520 to ground. When the brushes of the finder switch are accurately centered on the terminals of the calling line, brush 520 engages an insulating segment of commutator 521, and relay 504 releases its armatures. Relay 504 opens the circuit of the 90 up-drive power magnet 506 and the brush shaft 508 ceases its upward movement.

Relay 106, which also energizes in series with relay 522, opens the holding circuit of relay 107. Relay 107, being of the slow to release type, does not retract its armatures immediately after its circuit is opened by the energization of relay 106. Although the right-hand winding of relay 106 does not furnish sufficient magnetic flux to attract the armature, said winding will maintain the attraction of the armature, once it has been operated by the energization of the left-hand winding. Consequently, relay 106 will remain in its operated condition as long as relay 107 maintains its armature attracted to hold the circuit for the right-hand winding of said relay 106 closed. 105

As soon as the finder switch leaves its normal position the off normal contact 525 is closed and relay 524 becomes energized. Relay 524 completes a circuit from battery through the left-hand winding of relay 500 to ground at the contact and inner left-hand armature of relay 524. Relay 500 serves to indicate that the finder switch is busy and to extend the starter wire 315 forward to the armature of the corresponding relay 501 at the next finder switch, as will be more fully explained hereinafter. The operation of relay 524 causes the energization of relay 707 at the district selector switch by means of a circuit from battery through the winding of relay 707, conductor 715, contact and inner right-hand armature of relay 524, conductor 716, contact 702 (1 to 10) of sequence switch 700, to ground. Relay 707 being energized, a circuit is established for relay 706 as soon as relay 504 releases its armatures 120 at the end of the movement of the finder 130

switch. This circuit may be traced from ground through the outer left-hand armature and back contact of relay 504, conductor 532; contact and outer right-hand armature of relay 524, conductor 717, winding of relay 706, contact 705 (1 to 15), front contact and left-hand armature of relay 707, conductor 718, to battery and ground at the left-hand normal contact of relay 523. Relay 706 becomes energized and closes a circuit for driving sequence switch 700 out of position 1 and into position 2. This circuit leads from battery through the winding of sequence switch 700, contact 701 (1), contact and left-hand armature of relay 706 to ground.

Relay 706 also closes a circuit for the operation of the cut-off relay 103 of the calling subscriber's line 100. This circuit leads from battery through the right-hand armature and front contact of relay 706, conductor 719, brush 513, terminal 517, conductor 125, winding of relay 103 to ground. Relay 103 opens the circuit above traced for the line relay 104, permitting the latter to release its armatures. The release of the left-hand armature of relay 104 removes ground from conductor 115, and permits the deenergization of relay 105, provided no other line relay corresponding to relay 104 in the A group is energized at this time. Relay 105 releases its armature. The time required for the deenergization of the slow to release relay 107 is so taken that said relay maintains its armatures attracted for an interval following the operation of relay 105. Consequently, relays 107 and 106 maintain their energized condition following the seizure of the line terminals by the finder switch for a time long enough to allow the cut-off relay 103 to become energized to in turn permit the deenergization of the group relay 105 in case no other line in the group is calling. When, therefore, relay 107 and relay 108 become deenergized, the conductor 122 is open at the armature and contact of relay 105, and relay 108 cannot be reoperated due to the same call to start a second finder switch hunting.

The calling subscriber's line has thus been extended over brushes 515 and 514 of a finder switch in the A group, conductors 533 and 534 to sequence switch contacts 710 and 711 at the district selector switch. By means of the usual sender selector switch (not shown) the subscriber's line may be further extended over conductors 720 and 721 to an idle register sender. A district selector switch substantially of the character as the one employed herein, having an individual sender selector for associating the subscriber's line with an idle register sender, is shown and described in detail in the patent to Stearn and Scudder, No. 1,395,977 granted November 1, 1921. The

calling line having been extended to a register sender, the calling subscriber may proceed to transmit impulses by means of his dial 126 to set up the designation of the called line on the registers of the sender. Following the registration of the desired number the sender operates to control the selective movement of the switch shown in Fig. 7 to set the brushes 712, 713 and 714 on a trunk leading to the proper succeeding switch, and thereafter to control such switch and as many other switches as may be involved in the particular connection being extended. During the time that the switches are being positioned under the control of the sender, the sequence switch 700 is advanced from position to position in the manner fully described in the above mentioned Patent No. 1,395,977, granted November 1, 1921, until it reaches position 12, which may be taken as the talking position. When sequence switch 700 leaves position 9 $\frac{1}{2}$, conductors 720 and 721 are disconnected from the calling subscriber's line. As sequence switch 700 reaches position 9 $\frac{3}{4}$, the right-hand contacts 710 and 711 are closed to extend the calling line through to the left-hand windings of the repeating coil 709. Relay 708 being thus included in series with battery and the calling line, becomes energized. As sequence switch 700 leaves position 10, contact 702 is opened and the original energizing circuit of relay 707 is interrupted, but this relay remains operated in a circuit from battery through the winding thereof, armature and contact of relay 708, inner right-hand armature and contact of relay 707, contact 703 (12 to 184) to ground.

At the end of the conversation the calling subscriber replaces his receiver to the switch-hook and relay 708 releases its armature. Relay 708 opens the circuit of relay 707, which also becomes deenergized. The sequence switch 700 is then driven into position 18 as by means of the following circuit: battery, through the winding of the magnet of said sequence switch, lower contact 701 (10 to 17), contact and outer right-hand armature of relay 707 to ground. In this position of sequence switch 700, the relay 523, individual to the finder switch, is energized in a circuit from battery through the left-hand normal contact of said relay, conductor 718, left-hand armature and back contact of relay 707, contact 704 (17 to 18), conductor 722, winding of relay 523, and contact and outer left-hand armature of relay 524 to ground. Relay 523 becomes energized and locks up in a circuit from battery over its make-before-break contact and inner left-hand armature, winding of said relay to ground at the outer left-hand armature of relay 524. In any suitable manner, such as that described in the above mentioned Patent No. 1,395,977, granted No.

vember 1, 1921, the district switch shown in Fig. 7 may be restored to normal as soon as sequence switch 700 reaches position 18, following which said sequence switch is advanced into position 1 in the usual way.

With relay 523 energized a circuit is completed as follows for restoring the operated finder switch to normal: battery, through the winding of downdrive power magnet 10 507, contact and inner right-hand armature of relay 523 to ground. Power magnet 507 causes the brush shaft 508 to move downwardly. On reaching the normal position the brush shaft 508 opens the off normal 15 contact 525, causing thereby the deenergization of relay 524. Relay 524 opens the holding circuits of relays 500 and 523. Relay 523 causes the deenergization of the downdrive power magnet 507 and relay 20 500 renders the finder switch available for further calls.

It will next be assumed that the subscriber of a line, such as line 110 in the B subgroup of the brush group illustrated in 25 Fig. 1, wishes to obtain a telephone connection. The removal of the receiver from the switch hook causes the energization of the line relay 111 in a circuit including conductors 119 and 120. Relay 111 completes 30 a circuit for the group relay 112, which corresponds identically with the group relay 105 of the A subgroup. Relay 112 completes a circuit from ground over its contact and armature, contact and armature of 35 relay 113, left-hand armature and back contact of relay 114, left-hand winding of relay 118, conductor 116, outer left-hand armature and contact of relay 302, outer left-hand armature and contact of relay 402, contact and armature of stepping magnet 408 40 to battery and ground. Relay 118, which corresponds to relay 108, becomes energized in this circuit and locks up in a circuit as follows: ground, through the right-hand 45 normal contact of relay 114, right-hand winding and front contact and inner right-hand armature of relay 118, conductor 127, terminal 409, brush 404, assuming the preference switch to be standing in its first position, left-hand armature and back contact of 50 relay 400, conductor 410, back contact and right-hand armature of relay 301, conductor 318, winding of relay 402 to battery and ground. Relay 118 operates in the same 55 manner as explained in connection with relay 108 to close a circuit for the trip magnet 505 controlling the sets of brushes of the A and B groups of finder switches having access to the terminals in which the lines 60 of this particular brush group appear. This circuit leads from ground through the contact and inner left-hand armature of relay 118, thence as above traced over conductor 124 to the winding of magnet 505. It will 65 be observed that a call originating in the

B subgroup results in the operation of relay 118 individual to this subgroup which locks up in series with relay 402 of the common starter circuit, which corresponds to the relay 302 used in connection with calls 70 originating in the A subgroups.

Relay 402 opens the conductor 116 to prevent the energization of other relays similar to 108 and 118, and also closes a circuit at its inner right-hand armature and front contact for stepping magnet 408. Furthermore, relay 402 completes a circuit from ground through its outer right-hand armature and contact, conductor 411, left-hand normal contact of relay 403, brush 406, terminal 412, assuming the preference switch to be standing in its first position, conductor 413, inner left-hand armature and back contact of relay 607, winding of relay 611 to battery and ground. Relay 611 is 80 individual to the finder switch indicated at 600 in the B group of finders and corresponds to the relay 504, shown in Fig. 5. The energization, therefore, of relay 611 brings about the operation of the idle finder 85 switch 600, which advances its tripped set of brushes into engagement with terminals 620, 621, 622 and 623 of the calling subscriber's line in the B subgroup. From this point on the establishment and release of 90 the connection proceeds in the same manner as the call discussed in detail above.

Considering the two calls above described, one occurring in the A subgroup and the other in the B subgroup of the brush group 100 illustrated in Fig. 1, it was assumed that the brushes 304 and 404 were standing in both cases on their first position terminals. As already stated, with these brushes on their first position terminals preference is given 105 to the first brush group shown in Fig. 1 over all succeeding brush groups in the event of simultaneous calls. For example, assume that with the preference switch in its first position a call originates in the A subgroup 110 of the first brush group shown in Fig. 1, and, at the same time, a call originates in the A subgroup of the second brush group illustrated in Fig. 2. As already explained, relay 108 and relay 208 become energized 115 in response to these calls by means of circuits closed through their left-hand operative windings and conductor 116. Relay 108 is locked up over its right-hand winding in a circuit including conductor 117, which 120 leads directly through the brush 304 of the preference switch to the winding of relay 302. Relay 208, however, of the second brush group has a path completed as follows for its right-hand winding: ground, 125 through its right-hand winding and front contact and inner right-hand armature, conductor 201 to the second terminal 319 of the preference switch. Since the preference switch brush 304 is standing in its 130

first position, the above traced path for the right-hand winding of relay 208 fails to be completed through to the winding of relay 302. Another path is closed as follows: 5 ground through the right-hand winding and front contact and inner right-hand armature of relay 208, conductor 202, and back contact and outer right-hand armature of relay 118 to the back contact and inner right-hand armature of relay 108. Since relay 108 is energized, this circuit is also opened and, consequently, relay 208 of the second 10 brush group must release its armatures as soon as relay 302 becomes energized in series with relay 108. Hence, where two calls originate in different brush groups simultaneously, the one having the highest order of preference, as determined by the position of the preference switch, will succeed in 15 gaining access to the common starter circuit and the other call will necessarily fail. From an inspection of the drawing it will be seen that the other brush 404 of the preference switch governs in a similar manner 20 the order in which the different B subgroups may obtain access to the common starter circuit shown in Figs. 3 and 4.

With the preference switch in a given position, assigning first preference to a particular brush group, if a call originates in 30 any other brush group, it may succeed in gaining access to the common starter circuit provided no call occurs simultaneously in any group having a higher order of preference at that particular time. For example, assume that a call is initiated on the line 230 of the B subgroup of the third brush group, while the preference switch is standing in its first position, namely, in the position to which the first preference is awarded 35 to the first brush group. Relay 238 becomes energized in response to the call and locks up over its right-hand winding since none of the relays 108, 118, 208 and 218, belonging 40 to groups having a higher order of preference, are energized at this time. The locking circuit for relay 238 may be traced from ground through the right-hand winding and front contact and inner right-hand armature of relay 238, conductor 203, back contact and outer right-hand armature of relay 208, back 45 contact and inner right-hand armature of relay 218, conductor 204, back contact and outer right-hand armature of relay 108, back contact and inner right-hand armature of relay 118, conductor 127, terminal 409, brush 50 404, and thence, as above described, to battery and ground, through the winding of relay 402. Relay 402 operates, as explained, 55 to initiate the movement of an idle line finder switch of the B group to make connection with the calling subscriber's line. Following the extension of each connection the preference switch brushes 304 and 404 are 60 advanced by the stepping magnet 408 to es-

tablish a new order of preference among the brush groups. In this manner an equality of service is given to all subscribers' lines and no particular group of lines will be favored by reason of its location in the finder 70 switches.

It was described hereinbefore how the preference switches, shown at the right of Figs. 3 and 4, are advanced from position to position following the operation of a 75 finder switch in the A and B groups. With the brush 306 of the switch shown in Fig. 3 standing in its first position, the starter wire is extended first to the armature of relay 500, individual to the first finder in 80 the A group, namely, the one shown in detail in the drawing. Should this finder be idle when a call originates, it will be taken for use in preference to all succeeding finders. Following the operation of the first 85 finder, the brush 306 advances to its second position terminal, whereby the starter wire is extended to a corresponding armature of relay 501, individual to the second finder switch in the A group, and this switch 90 now becomes the first preference. Correspondingly, following the operation of each finder switch the preference switch advances one position and gives the first choice of selection to a new finder switch. 95 If the particular finder to which the first preference is given by the switch arm 306 be busy, then the starter wire will be extended over the armature and front contact of the relay, such as 500, to the armature of the corresponding relay of the next 100 finder switch in order. This manner of extending the starter wire can be more fully seen by referring to the relays 607, 608, 609 and 610 of the four finder switches of the 105 B group, shown in Fig. 6. Consider that the preference switch pertaining to the B group of finders is standing with its brush 406 on the first position terminal 412. In 110 this position first preference is given to 115 finder switch 600, that is to say, the starter wire leads directly over conductor 413 to the inner left-hand armature of relay 607. Should the first finder switch 600, however, be engaged at the time a call originates in one of the B subgroups, then the 120 starter wire is extended by way of brush 406, terminal 412, conductor 413, inner left-hand armature and front contact of relay 607, conductor 628 inner left-hand armature 125 and back contact of relay 608, assuming 130 finder switch 601 to be idle, through the winding of relay 612. Relay 612 thereupon serves to start the finder switch 601 into operation to find the calling line. In a similar manner the starter wire may be extended over the armatures and front contacts of all relays 607, 608, 609, etc., that represent busy finder switches until it finally reaches an idle switch.

It will lastly be considered that a call is initiated on a line in the A subgroup, such as line 100, when all of the A finder switches having first choice access to such line are busy. Since all of the finders A are busy, relays 500, 501, 502, 503, etc., are all energized, consequently, a series circuit is closed from ground through the contacts and left-hand armatures of these relays, conductor 320, left-hand winding of relay 300 to battery and ground. Hence, when the group relay 108 is energized, its locking circuit is closed as follows: ground, through the right-hand normal contact of relay 107, right-hand winding and front contact and inner right-hand armature of relay 108, conductor 117, terminal 309, brush 304, provided the preference switch is standing in its first position, left-hand armature and front contact of relay 300, winding of relay 301 to battery and ground. Relay 301 attracts its armatures and completes a circuit from battery through the winding of relay 402, conductor 318, right-hand armature and front contact of relay 301, conductor 321, contact and outer right-hand armature of relay 400 to ground. Relay 402 therefore becomes energized in response to the initiation of a call in the A subgroup. Relay 402, as already explained, causes the energization of stepping magnet 408, opens the circuit to conductor 116 to prevent the initiation of other calls, and closes the starter wire through brush 406 to an idle line finder switch in the B group. The chosen finder switch is operated, moves over the first ten terminals and hunts for the terminals of the calling line in the upper section of ten terminals. Since it is assumed line 100 is calling and provided the finder switch 600 happens to be the one taken for use, the set of brushes 604 are driven into engagement with the terminals 615, 616, 617 and 618 of the calling line. When the calling line has been found, relay 403 becomes energized in the manner similar to that explained in connection with relay 303 and causes the energization of stepping magnet 407. When later relay 402 deenergizes due to the energization of relay 107, relay 403 releases its armatures and stepping magnet 407 advances the brushes 405 and 406 forward one position, thereby changing the order in which the finder switches of the B group are taken for use.

What is claimed is:

1. In a telephone system, subscribers' lines arranged in a plurality of groups, automatic switches arranged in a plurality of groups for serving all of said lines, and arranged to be taken for use in a given order, each group of switches arranged to serve as first choice a different one of said groups of lines, means responsive to a call

in any group of lines to operate an automatic switch in the group normally serving such group of lines as first choice, means for operating a switch in another group when all the switches normally serving as first choice the group of lines containing the calling line are busy, a preference device for changing the order in which the switches of a group are to be taken for use, and means responsive to the operation of a switch for operating said device whether the operated switch is taken to serve its first choice group of lines or another group.

2. In a telephone system, subscribers' lines arranged in a plurality of groups, automatic switches arranged in a plurality of groups for serving all of said lines, and arranged to be taken for use in a definite order, each group of switches arranged to serve as first choice a different one of said groups of lines, means responsive to a call in any group of lines to operate an automatic switch in the group normally serving such group of lines as first choice, means for operating a switch in another group when all the switches normally serving as first choice the group of lines containing the calling line are busy, a step-by-step preference switch for changing the order in which the automatic switches of a group are to be taken for use, and means responsive to the operation of an automatic switch for advancing said preference switch whether the operated automatic switch is taken to serve its first choice group of lines or another group of lines.

3. In a telephone system, subscribers' lines arranged in a plurality of groups, automatic switches arranged in a plurality of groups for serving all of said lines, and arranged to be taken for use in a given order, each group of switches arranged to serve as first choice a different one of said groups of lines, means responsive to a call in any group of lines to operate an automatic switch in the group normally serving such group of lines as first choice, means for operating a switch in another group when all the switches normally serving as first choice the group of lines containing the calling line are busy, a preference device for each of said groups of switches for changing the order in which the automatic switches of such groups are to be taken for use, and means responsive to the operation of an automatic switch in any group for operating the preference device individual to such group whether the operated switch is taken to serve its first choice group of lines or another group.

4. In a telephone system, subscribers' lines arranged in a plurality of groups, finder switches arranged in a plurality of groups for serving all of said groups of lines, and arranged to be taken for use in a given order, each group of finders arranged

to serve as first choice a different one of said groups of lines, means responsive to a call in any group of lines to operate a finder switch in the group normally serving such 5 group of lines as first choice, means for operating a finder in another group when all of the finders normally serving as first choice the group of lines containing the calling line are busy, a preference device 10 for changing the order in which the finders of a group are to be taken for use, and means responsive to the operation of a finder switch for operating said device whether the operated finder is taken to serve his 15 first choice group of lines or another group.

5. In a telephone system, subscribers' lines arranged in two groups, a plurality of finder switches arranged in two groups, and arranged to be taken for use in a given order, 20 each group of finders arranged to serve both groups of lines and to serve a different one of said groups of lines as first choice, means responsive to a call in either group of lines to operate a finder switch in the 25 group normally serving as first choice the group of lines containing the calling line, means for operating a finder in the other group when all of the finders normally serving as first choice the group of lines containing the calling line are busy, a preference device for changing the order in which the finders of a group are to be taken for use, and means responsive to the operation 30 of a finder switch for operating said device whether the operated finder is taken to serve a line in its first choice group or a line in the other of said groups of lines. 35

6. In a telephone system, telephone lines divided into a plurality of groups, automatic 40 switches arranged in a plurality of groups for serving all of said lines and arranged to be taken for use in a given order, each group of switches serving as first choice a different one of said groups of lines, means for operating 45 normally the automatic switch in the group serving as first choice the group of lines containing a calling line, means for operating a switch in another group when all the switches normally serving the calling 50 group are busy, means for changing the order in which the switches of a group are to be taken for use, and means rendered effective upon the operation of a switch for operating said last mentioned means whether the operated switch is taken to serve its first 55 choice group of lines or another group.

7. In a telephone system, telephone lines divided in a plurality of groups, automatic

switches arranged in a plurality of groups for serving all of said lines and arranged to be taken for use in a definite order, each group of switches serving as first choice a different one of said groups of lines, means responsive to a call in any group of lines to operate an automatic switch in the group normally serving the calling group as first choice, means for operating a switch in another group when all of the switches normally serving a calling group are busy, means for changing the order in which the 60 switches of a group are to be taken for use, and means responsive to the operation of a switch for rendering said last mentioned means effective whether the operated switch is taken to serve its first choice group of 65 lines or another group. 70

8. In a telephone system, subscribers' lines arranged in a plurality of groups, automatic switches arranged in a plurality of groups for serving all of said lines and arranged to be taken for use in a given order, each group of switches arranged to serve as first choice a different one of said groups of lines, means responsive to a call in any group of lines to operate an automatic switch in the group 80 normally serving said group of lines as first choice, means for operating a switch in another group when all the switches normally serving as first choice a group of lines containing the calling line are busy, and a preference device for changing the order in which the switches of a group are to be taken for use. 85

9. In a telephone system, subscribers' lines arranged in a plurality of groups, automatic 90 switches arranged in a plurality of groups for serving all of said lines and arranged to be taken for use in a given order, each group of switches arranged to serve as first choice a different one of said groups of lines, means responsive to a call in any group of lines to operate an automatic switch in the group 95 normally serving said group of lines as first choice, means for operating a switch in another group when all the switches normally serving as first choice a group of lines containing the calling line are busy, and a preference device for each of said groups of 100 switches for changing the order in which the switches of said groups are to be taken for 105 use. 110

In witness whereof, I hereunto subscribe my name this 15th day of September A. D., 1920.

FRANK S. IRVINE.
